UNITED STATES PATENT OFFICE.

JOHN D. LAWRENCE AND WILLIAM G. FLEISCHAUER, OF DETROIT, MICHIGAN,
ASSIGNORS TO TERNSTEDT MANUFACTURING COMPANY, OF DETROIT, MICHIGAN, A CORPORATION OF MICHIGAN.

WINDOW-LIFTER STOP.

1,311,168.

Specification of Letters Patent. Patented July 29, 1919.

Application filed September 16, 1918. Serial No. 254,171.

To all whom it may concern:

Be it known that we, JOHN D. LAWRENCE and WILLIAM G. FLEISCHAUER, citizens of the United States, residing at Detroit, county 5 of Wayne, State of Michigan, have invented a new and useful Improvement in Window-Lifter Stops, of which the following is a specification.

This invention relates to a window lifter stop which automatically engages when the operator ceases to turn the window lifting apparatus and automatically disengages when the operator begins the turning operation.

15 Window lifters are now quite extensively used in closed automobile bodies and window lifter stops have heretofore been manufactured. However, some were open to the objection that they involved too many parts 20 from a mechanical standpoint, and some were noisy. In our improved window lifter stop the stop is absolutely noiseless and takes immediate effect upon release of power and is simple in its construction. This will 25 more fully appear in the specification following.

In the drawings.—

Figure 1 is an elevation of the casing employed in the top of a window lift of an 30 automobile, the casing being broken away to show the interior mechanism.

Fig. 2 is a top view of this casing with the window stop mechanism shown in section.

Fig. 3 is a detail of the cam.

35 Fig. 4 is a fragmentary elevation of the female clutch member.

Fig. 5 is an elevation of the male clutch member.

Fig. 6 is a detail of the driving pinion.

40 Fig. 7 is a detail of the shaft.

a designates the housing for the gear wheels and stop of a window lift now in common use on automobile bodies. *b* represents the window lifting chain, *c* the large 45 driven gear, *d* the driving pinion, *e* the crank spindle which can be turned by a crank (not shown) placed upon the flattened end *f*.

The pinion *d* is not directly connected for 50 driving with the crank spindle *e*. The crank spindle is flattened at *g* to fit into the rectangular-like recess *h* of the cam *i*. Screwed to the housing is a female stationary clutch part *k* having a coned socket. Into this

socket is adapted to fit the male clutch part 55 *l* which can slide longitudinally of the crank spindle *e*. Both the cam *i* and the male clutch part *l* have segmental slots *m* and *n* respectively to receive the driving pin *o* fast to the driving pinion *d*. This driving 60 pinion *d* is rotatably secured to the back of the housing by the flanged bushing *p* and nut *q*. The coiled spring *r* engaging the inside face of the housing bears against the male clutch part and holds it in engagement 65 with the female clutch part. The washer *s* reduces the friction on the parts in turning.

The operation is as follows: The operator turns the crank spindle *e* upon which the cam *i* is fast. The cam *i* fits in the recess *z* 70 in the front of the male clutch part and is somewhat smaller than this recess so that it has a certain amount of freedom for turning over the beveled side walls *t*. Obviously turning upon these bevels will force the male 75 clutch part longitudinally backward upon the crank spindle and disengage the two clutch parts to allow freedom of movement for the window lifting mechanism. Immediately the power is released from the crank 80 spindle, the spring forces the two clutch parts together and they engage easily and noiselessly to stop the window lifting mechanism and hold the window in any desired position. The cam and spindle will centralize 85 themselves due to the bevel acting upon the cam through the efforts of the spring.

This construction is not only simpler than those heretofore made but it is noiseless and the stop takes immediate effect regardless 90 of the position of the window as distinguished from the old stops which usually require the window to shift back slightly so as to bring two positive clutch parts into registry.

95 What we claim is:

1. A window lifter stop, comprising a pinion provided with a driving pin projecting laterally therefrom, a cam having a segmental slot in which the pin protrudes, a 100 crank spindle fast to the cam, a pair of friction clutch parts, which engage by friction only, and a spring for normally holding them in engagement, the said spindle operating to turn the cam which initially disengages the clutch parts and then picks up the driving pin to drive the driving pinion. 105

2. A window lifter stop, comprising a

pinion rotatably supported, a cam having lost motion connections therewith, a spindle fast to the cam, a female cone clutch part, a male cone clutch part, the latter provided 5 with beveled portions upon which the cam rides, and a spring for keeping the two clutch parts together, the turning of the spindle serving to throw the cam against the beveled portions of the male clutch part to 10 disengage the clutch parts before the cam comes into direct driving relation with the pinion.

3. A window lifter stop, comprising a housing, a pinion rotatably supported on 15 one wall of the housing, a flanged sleeve for effecting such support, a spindle rotatably supported in this sleeve and the other wall

of the housing, a cam fast to the spindle and adjacent the pinion, lost motion connections between the cam and pinion, a female 20 clutch part stationarily secured to the housing, a male friction clutch part on the spindle engaging with the female friction clutch part and having a cam surface by which it is shifted longitudinally on the spindle by the 25 cam in taking up the play in the lost motion connection with the pinion, and a spring for pressing the two clutch parts together.

In witness whereof we have hereunto set 30 our hands on the 11th day of September, 1918.

JOHN D. LAWRENCE.
WILLIAM G. FLEISCHAUER.
